Carl H. Crawford

ATTORNEY

UNITED STATES PATENT OFFICE.

EDWARD A. WHITE, OF LEWISTON, IDAHO.

TRANSPORT STAND.

Application filed April 5, 1926. Serial No. 99,871.

The object of this invention is to provide improved means for facilitating the handling of boxed goods to be sorted and packed.

5 A further and special object of the invention is to provide an improved box stand adapted to be inter-changeably used by packers and sorters and functioning not only to hold the boxed goods during the sorting or 10 packing process, but also serving as a means of transit of the boxed goods to and from the table or other device at which the sorting and packing operations are carried on.

Thus it is a feature of my invention to 15 provide a rolling box stand that may be readily advanced to and from the sources of supply and conveyance of the boxed goods.

It is a feature of the invention to provide the stand with a novel box holding means 20 designed to hold the box in such a position as to facilitate access thereto by a sorter or packer, said holding means being also designed to perform the additional function of facilitating the loading onto or unloading 25 off from said stand of boxes containing goods, such as apples, thereby avoiding lifting by hand, of these relatively heavy containers.

Other features and objects of the invention 30 will be more fully described in connection with the accompanying drawing and will be more particularly pointed out in and by the appended claim.

In the drawing:—

35 Fig. 1, is a view in elevation of a plant arrangement and structure incorporating the invention in the most improved form.

Fig. 2, is a view in side elevation of my improved stand showing an apple box thereon.

40 Fig. 3, is a view looking from the right of Fig. 2.

Fig. 4, is a view looking from the left of Fig. 2.

Like characters of reference designate similar parts throughout the different figures of the drawing.

I will first describe a plant construction, which I claim as novel, and which also illustrates a highly advantageous use of the 50 device of my invention, a special feature being that one type of my stand is inter-changeably available for different operatives.

The floor line is designated at 1, and I have shown a motion storage table 2 which 55 is rotated by a shaft 3, mounted in bearings

4 and 5, and which is specifically described and claimed in my pending application filed March 30, 1926, Serial No. 98,629. At the left of the table 2, is what I will broadly term a sorter's conveyor 6, which may be 60 of any approved type and on which boxes 7, filled with unsorted apples are conveyed to the sorters, whose position we will say is at the left of table 2. At the right of said table I have shown what I will term a packer's 65 conveyor 8, of any approved form, which is adapted to convey away the boxes 9, which have been packed with apples. I have shown the conveyor 6, of slightly greater height than the conveyor 8, for a purpose which will 70 presently appear. Now generally speaking, the boxes of unsorted apples 7, are conveyed to the sorters and must be transferred off from the conveyor 6, and supported in a position to render the contents accessible to 75 the sorter adjacent the table 2, so that the apples can be sorted out as to grades, or sizes, or in some instances both, the different kinds of apples being deposited on the table 2. The packer, at the other side of the table 80 2, must have an empty box held in an accessible position so that the packer can take apples of a certain grade off from table 2, and pack them in the box 9. After a box has been packed full of apples, it must be 85 transferred to conveyor 8, where it is carried to a suitable point of deposition. Of course, both sorters and packers stand upright when 90 working, and heretofore it has been necessary for sorters to lift a box of unsorted apples 90 from the floor onto a suitable bench from which they can work. It has also been necessary for the packer to lift a fully packed box off from the bench and deposit it on the floor in order to make room for an empty box. 95 Where female help is employed as sorters and packers, this required the services of one or two men to do the lifting of boxes, and frequently the sorters or packers had to wait for one of the men to perform this function. 100

Now it is the object of this invention to avoid such delay, and to also provide a novel arrangement whereby the sorters and packers, even when girls are so employed, can readily shift the filled boxes and transport them as required, with a minimum of effort and a maximum of speed, thereby avoiding entirely, the necessity of men for lifting the filled boxes.

Therefore, I will next proceed to describe 110

my improved transportable box support and stand which is more particularly shown in Figs. 2 to 4.

As shown, my improved stand includes a top 10, supported on suitable legs 11 that may be connected at 12, to render the structure rigid. Because my stand is partly designed to transport goods, it is a feature to provide a rolling stand, or a stand having anti-friction means whereby it may be readily shifted from place to place on the plant floor. I therefore prefer to mount the legs 11 on roller casters 13, of an approved type.

On the top 10, I provide box supporting means which involves a fixed and a rolling element, and it is a feature of my invention to so construct and combine these elements so that the box will automatically seek a secure position by gravity, which position is preferably and advantageously an inclined position so as to render the contents more easily accessible. It is a further feature to employ a rolling box supporting element of such a character that a full box may readily be shifted on such element onto or off from the stand.

The said fixed supporting element is shown in the form of a rest head 14, having angularly disposed portions or sections 15 and 16, against which an end face 17, and a bottom face 18, of the box may repose. The short portion or section 15, functions more as an abutting section while the elongated section 16 functions more as slide and a supporting section. The head 14, is provided with a suitable base 19, which is anchored to the stand top 10. From Fig. 4, it will be seen that the head 14 engages a sufficient linear area of the box to provide a secure support without engaging the side portions thereof.

The remaining or rolling member of the support consists of a roller 20, rotatively mounted in a suitable bracket 21, which is suitably anchored to top 10. This roller 20, is disposed in sufficient spaced relation to support 14, and at such an elevation with respect thereto, as to throw the center of gravity preponderently toward the left of Fig. 2, so that the box will seek the position shown therein by gravity. I do not necessarily mean by this that the box will, itself, always slide into the position shown, but I do mean that the weight of the box, in this disposition, will greatly lighten the burden of the operator in putting or shifting the box onto the stand. It will also be clear that with the box in this position, either the sorter or packer can operate with a minimum of reaching.

Assuming that a sorter wanted a new

box, he will shift the stand to the dotted line position adjacent conveyor 6, and with the roller 20, nearest the conveyor. This conveyor is of such a height that it is on a substantial level with the top of roller 20. Thus, the box 7, can be shifted to the right of conveyor 6, onto roller 20, without lifting the box, and then after the box is on roller 20, a slight extra impulse will deposit the box in the correct position shown in Fig. 2. The stand is then shifted to the sorter's position adjacent the table as shown in full lines, and the sorter works at sorting out the apples until the box is emptied. He then merely lifts the empty box off from the stand and repeats the operation just described, of getting a new box from conveyor 6. Thus, he never has to lift a full box, only an empty box.

When a packer starts to pack, he will lift an empty box on the stand, as shown in full lines at the right of table 2. After he has packed this box full, he will shift his stand to the dotted line position adjacent conveyor 8. By pushing the box 9 to the right, over roller 20, which greatly facilitates this operation, and because the top of conveyor 8, is lower than, or even if on the same level as, the top of roller 20, the effort is of a minimum nature. While I have shown the conveyor 8, slightly lower than conveyor 6, this difference of height is not necessary, as in either loading a box onto the stand or unloading a box from the stand, the roller side of the stand will be disposed next adjacent the conveyor.

The vastly important feature is that I only have to provide one type and one size of stand, and that this stand is equally available and inter-changeably used by sorters and packers for loading and unloading. And further, this stand never requires a sorter or packer to lift a filled box.

It is believed that the device of my invention will be fully understood from the foregoing description, and while I have herein shown and described one specific form of my invention, I do not wish to be limited thereto except for such limitations as the claim may import.

I claim:

In a transportable box support, a rolling box stand, said stand having loading and unloading box supporting means comprising a roller, and a rest head having an abutment section, said head having an elongated supporting section inclined toward said roller and on which the box may slide down into position.

In testimony that I claim the foregoing as my own, I hereby affix my signature.

EDWARD A. WHITE.
